Patented July 17, 1923.

UNITED STATES PATENT OFFICE.

BENNIE F. OSTROWSKI, OF SAN JOSE, CALIFORNIA.

VANITY CASE.

Application filed January 25, 1923. Serial No. 614,861.

To all whom it may concern:

Be it known that I, BENNIE F. OSTROWSKI, a citizen of the United States, and resident of San Jose, in the county of Santa Clara and State of California, have invented certain new and useful Improvements in Vanity Cases, of which the following is a specification.

My invention relates to a combination 10 mirror and comb case which may be carried in a vest pocket on a gentleman's chain.

It is the object of my invention to provide a device of the character indicated in which the comb is carried in an individual 15 compartment of the case and is easily withdrawn for use by the releasing of a catch.

It is another object of my invention to provide a device of the character indicated in which the mirror is mounted upon a 20 hinged cover to enable the same to be swung outwardly when in use and protected against breakage when closed.

Yet another object of my invention is to provide a compartment in a device of the 25 character indicated adapted to receive a picture, stamps or other small objects.

A still further object of my invention is to provide a device of the character indicated which is simple in construction, easily 30 manufactured and one that is highly efficient in its practical use for the purposes above set forth.

In the drawing:—

Figure 1 is a sectional view on line 1—1 35 of Figure 2.

Figure 2 is a sectional view on line 2—2 of Figure 1.

Figure 3 is a front elevation of the case, parts being broken away.

Referring more particularly to the drawing I show a rectangular metallic case 1 having a partition 2 placed vertically therein in the position shown. At 3 is shown a second partition placed at right angles to partition 1 to form a comb carrying compartment 4 as shown. A second compartment being thus formed as at 5 in which a picture may be placed or if desired stamps or other small articles.

Hingedly mounted to the lower edge 6 of case 1 is a cover 7 having a mirror 8 mounted upon its inner side as shown. This cover may be swung outwardly as indicated in dotted lines in Figure 2 thus giving free

access to compartment 5 and allowing use of the mirror 8, the mirror being protected

from breakage when the cover is closed as is apparent. The cover 7 is held closed by means of a catch 9 secured to case 1 and passing through an orifice 10 in the cover as shown. This catch 9 is opened by pressing on pin 11 which projects through the top of case 1.

Mounted upon the lower portion of case 1 and within compartment 4 is a spring 12 65 engaging the lower end of comb 13 which passes through orifice 14 in case 1 as shown. The said comb is held from rattling in the compartment 4 by means of springs 15—16 70 mounted upon case 1 and partition 3 respectively as shown, the comb passing between the same.

Slidably mounted in orifice 17 in partition 2 is a catch member 18 having an upstanding portion 19 passing thru slot 20 75 in case 1 and bent to form a ring 21 as shown. Portion 22 of catch 18 engages a slot 23 in comb 13 as shown, and is held in this engaging position by means of spring 24 secured to case 1.

Ring 21 is used to secure the case to a watch chain if desired and is also used to slide catch 18 out of engagement with slot 23 in comb 13 whereupon the spring 12 forces the comb upwardly a distance as indicated in dotted lines in Figure 3, allowing the comb to be readily grasped in order to remove the same from the case 1 when it is desired to comb the hair.

The pin 11 is now depressed forcing catch 9 downwardly in slot 10 of cover 7 allowing the cover to be swung outwardly to bring the mirror in position for use.

The compartment 4 is closed off from view by partitions 2—3 while compartment 5 is open to view when the mirror is being used thus allowing the articles placed in the compartment to be easily reached.

Thus it is seen that I have provided a comb and mirror case which is simple in construction, easily manufactured, easily operated and highly efficient in its practical application.

It is to be understood, of course, that while I have herein shown and described the preferred embodiment of my invention that changes in proportion, materials, method of construction and operation may be made within the scope of the appended claims.

I claim:—

1. A vanity case comprising a body por-

- tion forming a receptacle, said receptacle having an orifice formed in one end thereof, a comb arranged in said receptacle and passing through said orifice, means for normally securing said comb in said receptacle, and means for partially ejecting said comb when said securing means is moved to an inoperative position.
5. A vanity case comprising a body portion forming a receptacle, a cover forming a closure for one side thereof, a compartment formed in said receptacle and provided with a single opening at one end thereof communicating with the exterior of said body portion, a comb arranged in said compartment and extending through said opening, and means for normally securing said comb in said compartment, said means being releasable from the exterior of said body portion.
10. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, and means for partially ejecting said comb when said securing means is moved to an inoperative position.
15. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, and means for partially ejecting the comb from the receptacle when said securing means is moved to an inoperative position.
20. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, and means for partially ejecting the comb from the receptacle when said securing means is moved to an inoperative position.
25. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, and means for partially ejecting the comb from the receptacle when said securing means is moved to an inoperative position.
30. A vanity case comprising a body portion forming a receptacle, a cover hingedly mounted thereon, a mirror arranged on the inner side of said cover, a comb arranged in said receptacle and extending through one end thereof and having a notch formed therein, a resiliently mounted pin normally engaging said notch, manually operated means for disengaging the pin from said notch, and resilient means for partially ejecting the comb from said receptacle when said pin is disengaged from said notch.
35. A vanity case comprising a body portion forming a receptacle, a cover hingedly mounted thereon, a mirror arranged on the inner side of said cover, a plurality of compartments formed in said receptacle, one compartment being permanently closed on all sides but having a slot formed in one end thereof, a comb arranged to enter said compartment through said slot, resilient means for securing said comb against lateral movement, means for normally securing said comb in said compartment and resilient means for partially ejecting the comb from the receptacle when said securing means is moved to an inoperative position.
40. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, chain engaging means arranged on said securing means, and means for partially ejecting said comb when said securing means is moved to an inoperative position.
45. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, and resilient means for partially ejecting the comb from the receptacle when said securing means is moved to an inoperative position.
50. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, and resilient means for partially ejecting the comb from the receptacle when said securing means is moved to an inoperative position.
55. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, and resilient means for partially ejecting the comb from the receptacle when said securing means is moved to an inoperative position.
60. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, and resilient means for partially ejecting the comb from the receptacle when said securing means is moved to an inoperative position.
65. A vanity case comprising a body portion forming a receptacle, a cover hingedly mounted thereon, a mirror arranged on the inner side of said cover, said receptacle having an orifice formed in one end thereof, a comb arranged in said receptacle and passing through said orifice, means for normally securing said comb in said receptacle, and resilient means for partially ejecting the comb from the receptacle when said securing means is moved to an inoperative position.

BENNIE F. OSTROWSKI.
